UNITED STATES PATENT OFFICE.

ALEXANDER M. GOW, OF DULUTH, MINNESOTA; AMERICAN EXCHANGE NATIONAL BANK OF DULUTH EXECUTOR OF SAID ALEXANDER M. GOW, DECEASED.

METALLURGICAL FURNACE.

Application filed June 17, 1921. Serial No. 478,260.

This invention relates to a metallurgical furnace of the type using gaseous fuel, and more particularly to a method and means for producing a higher flame temperature and more rapid combustion of the gas in such furnaces.

In furnaces of this character it is the usual practice to admit the air and gas alternately at the opposite ends of the furnace. 10 Because of the large volume required and the large volume of the products of combustion, the ports are necessarily of very considerable cross-sectional area. The air and gas ports are located adjacent each other, the air 15 port usually being superimposed upon the gas port. The two ports are usually separated by a refractory arch which not infrequently is water-cooled. In the usual construction the water-cooled end of the arch 20 terminates at about the end of the melting chamber. By this form of construction the air enters in a more or less flat layer the width of the air port, while the gas enters in a similar, although usually narrower layer 25 below the air. No provision is ordinarily made for insuring or positively forcing the two layers to mix, it being assumed that the lighter gas will gradually rise through the air. This intermixture takes place but slowly 30 however, and the effective flame does not begin until well into the furnace from the port ends.

The flame temperature is much lower than would be the case if the mixture of air and 35 gas had taken place in a mixing chamber before it entered the melting chamber of the furnace.

It is an object of the present invention to provide new and improved means for 40 causing the mixture of the air and gas before their entrance into the melting chamber, and further to cause this mixture without any reduction in the usual area of the ports, or other interference with the usual passage of 45 the gases and air.

It is a further object to provide means of this character which requires but a small amount of power and which may be applied to existing installations at relatively small 50 expense and without material alteration of existing structures.

Other and further objects will appear as the description proceeds.

Broadly, my invention consists in the introduction into the air or gas streams, or

both, of a jet or jets of air or oxygen under relatively high pressure. These jets serve to force the streams into each other and to cause the intermingling of air and gas. Jets may be provided above serving to force the air 60 down into the gas, or below serving to force the gas up into the air or in both places. They may be so disposed as to give a swirling motion to the combined stream of air and gas, with consequent effective intermingling 65 of the two components. The volume of this air under pressure may be very small compared to the total volume of air and gas. The number and location of the jets will depend somewhat upon the size and design of the 70 furnace. Preferably, the usual water-cooled gas port is reduced in length so that a mixing chamber is formed between the end of that port and the melting chamber. The air at high pressure will normally not be 75 as hot as the preheated air into which it is introduced and hence a small reduction of temperature occurs; but due to the relative quantities of the compressed and preheated air this cooling is relatively slight and is 80 very much more than compensated for by the increased efficiency of combustion. This reduction of temperature is much less than would be caused by constructions involving the water-cooled dampers or the like which 85 have been proposed for the purpose of directing the preheated air and gas streams together.

My invention is admirably adapted for use with the richer gases containing hydrocarbons such as coke oven gas or natural gas. Such gases must be broken down into their constituents, carbon and hydrogen, before combustion takes place. Heat and time are required to effect this breaking down but it is 90 impractical to heat such gases in regenerators because of the deposition of carbon. By causing the immediate intermingling of such gases with the heated air by the means of my high pressure jets, the gases are broken down in the mixing chamber and the furnace without deposition of carbon and in ideal condition for complete combustion within the chamber. Obviously some combustion will take place immediately the gas and air come into contact in the preliminary mixing chamber. This preliminary combustion will augment the temperature of the gases before their entrance into the melting chamber and complete combustion will take place therein 100 105 110

at a very high temperature. The amount of this preliminary combustion will depend somewhat on the amount of mixing of air and gas streams affected by my jets, and 5 consequently I propose to control this mixing by controlling the velocity and volume of the high pressure jets. This may, of course, be readily done by valves or similar means.

10 Under certain circumstances it may be desirable, instead of air to use either air so combined with oxygen as to materially increase the oxygen content, or possibly even pure oxygen. Such jets will not only mix 15 the air and gas but will aid very materially in the combustion and increase its temperature.

I have illustrated a preferred embodiment 20 of my invention in the accompanying drawing, in which the single figure shows a vertical longitudinal section through one end of an open hearth furnace equipped with my invention.

The furnace as shown comprises the melting chamber 5, mixing chamber 6, air port 7, air uptake 8, air slag pocket 9, also the gas port 10, gas uptake 11, and gas slag pocket 12. The gas port is surrounded by 25 the water-cooling element 13. A pair of nozzles 14 and 15 are placed respectively above and below the entrance from the mixing chamber 6 to the melting chamber 5. A similar nozzle 16 is provided at the upper 30 side of the air port and a nozzle 17 below 35 the discharge end of the gas port. As shown, these nozzles are all connected to pipes by which they are provided with compressed air, or oxygen, as has been stated. These nozzles may be provided, if desired, 40 with water-cooling elements or otherwise formed so as to protect them from heat in any desired manner. The provision of such means, however, forms no part of the present invention and need not be further 45 described herein.

The gas comes up through the slag pocket 12 and uptake 11 and out through the port 10. The preheated air comes from the checker chamber (not shown) through the 50 slag pocket 9, uptake 10 and out of the port 7 which straddles the gas port. These two streams of gaseous fluid are caused to mingle by the introduction of the high pressure jets from the several nozzles. If desired, the nozzles may be used selectively, 55 the nozzles 14 and 16 when used alone serving to force the air current downwardly into the gas current and to cause the mixed flow of air and gas to pass through the lower part 60 of the furnace. In the same manner, if it is desired to have the flame at a higher level in the furnace, only the jets 15 and 17 may be used. When all jets are used a more 65 thorough intermixture will be secured, but any one of the jets very materially increases

the intermixture of the air and gas and materially increases the temperature of the resultant flame and causes it to reach its efficiency at a point closer to the incoming end of the furnace.

It is not essential to my invention that the gas port be as short as that shown, and the various nozzles may be disposed in different positions according to the requirements of any particular furnace and construction.

I claim:

1. In a furnace, adjacently located large conduits for low pressure air and gas leading to a furnace chamber, and compressed air conduits having openings so located as to force an intermixture of the air discharging from the air conduit and the gas discharging from the gas conduit.

2. In a furnace, adjacently located large conduits for low pressure air and gas leading to a furnace chamber, and compressed air conduits having openings located adjacent the discharge opening of the air conduit upon the side thereof opposite the opening of the gas conduit whereby the compressed air is adapted to force the air into the gas.

3. In a furnace, adjacently located conduits for air and gas leading to a furnace chamber, and compressed air conduits having openings located adjacent the discharge opening of the gas conduit upon the side thereof opposite the opening of the air conduit whereby the compressed air is adapted to force the gas into the air.

4. In a furnace, a large gas port, a large air port superposed on said gas port, said ports being adapted to discharge large volumes of air and gas under low pressure and compressed air conduits each having a downwardly directed small opening adjacent said air port, the compressed air discharge therefrom being adapted to force the air from the air port to intermingle with the gas from the gas port.

5. In a furnace, a gas port, an air port superposed on said gas port, and compressed air conduits each having an upwardly directed opening adjacent said gas port, the compressed air discharged therefrom being adapted to force the gas from the gas port to intermingle with the air from the air port.

6. In a furnace, a gas port, an air port superposed on said gas port, compressed air conduits having upwardly directed openings and other compressed air conduits having downwardly directed openings adjacent said ports whereby the compressed air discharged from said openings causes the air and gas issuing from said ports to be intermingled.

7. In a furnace, adjacently located large conduits for low pressure air and gas leading to a furnace chamber, and compressed air conduits having openings of comparatively small area adapted to so discharge air under relatively high pressure as to cause an inter-

mingling of the air and gas discharged from said large conduits.

8. In a furnace, a melting chamber, gas and air ports discharging large volumes of low pressure gas and air toward said melting chamber into a mixing chamber intermediate said ports and melting chamber, and compressed air conduits having openings adapted to discharge jets of compressed air into said mixing chamber whereby the air and gas from said ports are intermingled.

9. The method of mixing gas and air in furnace operation which consists in causing

a premixture of large volumes of low pressure gas and air by the use of jets of air at 15 relatively high pressure.

10. The method of mixing gas and air in furnace operation which consists in introducing large volumes of air and gas at low velocity in adjacent streams and directing jets of air at relatively high pressure against said streams whereby they are caused to intermingle. 20

Signed at Duluth, Minnesota, this 11th day of June, 1921.

ALEXANDER M. GOW.
